D. R. BRUCE

LIQUID FUEL BURNER OF THE INJECTION TYPE

Filed Oct. 21, 1921

Inventor:
David Robertson Bruce
Assignee: The Boeing Company
7000 S. 35th Street, Seattle, Washington

UNITED STATES PATENT OFFICE.

DAVID ROBERTSON BRUCE, OF LONDON, ENGLAND.

LIQUID-FUEL BURNER OF THE INJECTION TYPE.

Application filed October 21, 1921. Serial No. 509,291.

To all whom it may concern:

Be it known that I, DAVID ROBERTSON BRUCE, a subject of the King of Great Britain, residing in London, England, have 5 invented certain new and useful Improvements in Liquid-Fuel Burners of the Injection Type, of which the following is a specification.

This invention relates to improvements 10 in liquid fuel burners of the injection type in which hydrocarbon fuel is mixed with air or other desired fluid and injected into a furnace or the like.

According to the invention the burner is 15 so arranged that the compressed air or other fluid is admitted to the burner between the fuel reservoir and the nozzle, the latter having two separate passages, one for the fuel and one for the air or other fluid, the mixing taking place at the point of issue of the 20 passages at the delivery end of the nozzle. The fuel reservoir may be provided with a suitable valve adapted to maintain a constant level of fuel therein, or a sight gauge 25 may be provided and the fuel regulated by hand for example.

In a suitable construction according to 30 the invention the burner comprises two separate chambers preferably formed in a single casting. One chamber carries the burner nozzle and has a suitable fluid opening within which said nozzle is arranged and by 35 which it is surrounded, said latter chamber being adapted to be placed in communication with the pressure fluid. The second chamber serves as a fuel chamber and is 40 fitted with a float operated valve for regulating the supply of fuel and communicates with the pressure chamber through a valve 45 controlled opening and also with the burner nozzle and with the fuel supply.

The burner nozzle is provided with two 50 inclined passages meeting at or about the extreme tip of the nozzle, and is mounted 55 on a tube which opens into the fuel chamber above the level of the fuel therein. One passage in the nozzle is connected by a pipe 60 with the fuel in the fuel chamber, the other passage being free and communicating with 65 the fuel chamber through the burner tube.

With all the above described construction, 70 on admitting the pressure fluid to the pressure chamber and opening the valve a portion of the pressure fluid passes into the fuel 75 chamber forcing the fuel through the fuel

passage in the burner nozzle and also passing through the free passage in the nozzle. At the same time a portion of the pressure fluid passes through the flame opening surrounding the burner nozzle thus increasing 80 the power of the flame. If the fluid pressure is cut off, the fuel supply to the nozzle at once ceases. The float operated valve in the fuel chamber may be adjusted to keep 85 the fuel level in the chamber constant.

To enable the invention to be fully understood it will now be described by reference to the accompanying drawing in which Fig. 1 is a longitudinal vertical sectional elevation of a burner constructed according to 90 one form of the invention.

Fig. 2 is a section on the line 2—2 Fig. 1.

As shewn in the drawing, the burner comprises two chambers 1, 2, preferably formed in a single casting, the chamber 1 being the 75 fluid pressure chamber and chamber 2 the fuel chamber. The chamber 1 is provided with an opening 3 for the fluid pressure, a fluid opening 4, and an orifice 5 communicating with chamber 2 controlled by a valve 6, the latter being here shewn as a mushroom valve positively operated by a rod 7 screw-threaded at 8 and rotatable in the wall of chamber 2 by means of a knob 9. The burner nozzle 10 is mounted on a tube 11, the other end of which is seated in the wall dividing the two chambers and opens into the fuel chamber 2. Two inclined passages 12, 13, are provided in the nozzle, meeting at a 80 point adjacent to the extreme tip of the 90 nozzle.

The passage 12 is for fuel and is connected with the fuel chamber 2 by a pipe 14 having a depending portion which dips below the surface of the fuel in chamber 2. 95 The passage 13 is for pressure fluid and is freely in communication with chamber 2 through the tube 11. A closure plate 26 secured into chamber 1 and having a central opening surrounding the nozzle is preferably provided.

The fuel chamber 2 is fitted with a cover 15 having an inlet 16 for the fuel terminating in a tube 17 extending down into the chamber and opening at its lower end into a 100 hollow flanged plug 18 having two lateral slots 19 for the passage of the fuel.

The flow of fuel through the slots 19 is regulated by a sleeve 20 slidably mounted on the plug 18 and pivoted at two points 21 110

to a carrier ring 22, the latter being pivoted at two points 23 to two stays 24 attached to the float 25 slidably mounted on the tube 17. The pivot points 21, 23, are so positioned that they form a gimbal suspension for the sleeve 20 which prevents jamming of the sleeve if the apparatus is working with the fuel chamber in an inclined position. The operation of the above described apparatus is as follows:—

Pressure fluid being admitted to chamber 1 through opening 3, the valve 6 being open the course of the pressure fluid is as indicated by the arrows, that is to say, a portion 15 of the fluid passes through the opening 4 surrounding the nozzle, a further portion passing through the valve 6 into chamber 2 and along tube 11 through the passage 13 in the nozzle. The admission of pressure fluid to chamber 2 causes the fuel to be forced through the pipe 14 and through the passage 12 in the nozzle. The float 25 moves according to the fluctuations of the fuel level in the chamber 2 causing the sleeve 20 25 to cover or uncover the slots 19 in the tube 17 and thus regulating the fuel supply as will be readily understood. If the fluid pressure is cut off from chamber 2, the fuel supply to the burner nozzle ceases at once 30 and the float rising on tube 17 cuts off the fuel supply to the chamber 2 as soon as it rises sufficiently to cause the sleeve 20 to cover the slots 19 completely.

It will be obvious that various arrangements of float operated valve may be employed in the fuel chamber 2. It is important that the fuel supply valve should be so adjusted that entry of fuel into the burner tube 11 is prevented. Further the depending end of tube 14 preferably extends down nearly to the bottom of the fuel chamber. As here shewn the various portions of the burner may be readily detached and replaced, the burner nozzle and the tube 11 being attached by screwing, the plate 26 surrounding the nozzle, and the tube 14 being readily removable. Further the cover 15 is preferably held down by suitable screws and on removal carries with it the whole of the float operated valve mechanism.

Having thus described the nature of my said invention and the best means I know of carrying the same into practical effect I claim:—

55 1. A liquid fuel burner having a fluid pressure chamber provided with a fluid opening, a nozzle arranged in and surrounded by said opening provided with two independent inclined passages meeting substantially at the tip of said nozzle, liquid fuel being admitted to one passage and pressure fluid to the other and to said fluid opening so that admixture of the fuel and the pressure fluid takes place substantially at the 60 tip of the nozzle.

2. A liquid fuel burner having a fluid pressure chamber provided with a fluid opening, a nozzle arranged in said opening provided with two independent inclined passages meeting substantially at the tip of said nozzle, a fuel reservoir having valve controlled communication with said fluid pressure chamber, a float operated valve for regulating the level of fuel in said reservoir, means to direct liquid fuel from said reservoir to one of said inclined passages, and means to supply pressure fluid from said fuel reservoir to the other of said inclined passages.

3. A liquid fuel burner having a fluid pressure chamber provided with a fluid opening, a burner nozzle arranged in said fluid pressure chamber, and surrounded by said opening, said nozzle being provided with two independent passages meeting substantially at the tip of said nozzle, a fuel chamber, and a valve interposed between said pressure fluid chamber and said fuel chamber, to permit pressure fluid to pass into the fuel chamber to force fuel and fluid therefrom through the passages in said nozzle to the combustion chamber thereof.

4. A liquid fuel burner comprising a fuel reservoir provided with a tube through which fuel is admitted from the source of supply, the end of said tube within the chamber terminating in a hollow plug portion having a fuel opening or openings in the side thereof, a float, a sleeve slidable on said plug portion and pivotally attached to said float, said float being operated by the fluctuations of the fuel level for controlling by means of said sleeve the passage of fluid through the opening in said plug portion.

5. In a liquid burner, a fuel tube having at least one fuel opening in the side thereof, a float and a sleeve to slide over said fuel opening and control the flow of liquid therethrough, said sleeve being freely suspended from and movable with said float by means including a gimbal.

6. A liquid fuel burner of the injection type having a fuel chamber, a fluid pressure chamber communicating with said fuel chamber, a burner nozzle arranged in said fluid pressure chamber in communication with said fuel chamber and a valve to control the admission of fluid under pressure from said fluid pressure chamber to said fuel chamber whereby the supply of fuel and fluid to said nozzle may be regulated.

7. A liquid burner comprising a fuel reservoir, a fuel supply tube terminating in a hollow plug provided with at least one fluid opening in the side thereof, a float slidable on said tube, a sleeve slidable on said plug to regulate the flow of fuel through said opening and gimbal suspension means between said float and said sleeve to effect the transmission of movements of said float

produced by fluctuations of the fuel level to said sleeve to control the passage of fluid through said opening.

8. A liquid fuel burner having a nozzle
5 provided with independent passages for
fuel and fluid meeting substantially at the
tip thereof, a fuel reservoir having passages
communicating with the fuel and fluid pas-
sages of said nozzle respectively with the
10 lower and upper portions of said fuel res-

ervoir, a pressure fluid chamber having a fluid discharge opening surrounding said nozzle and valve controlled communication between said fluid chamber and said fuel chamber to regulate the supply of fluid un- 15
der pressure to force fuel and fluid respec-
tively to said nozzle.

In testimony whereof I have signed my
name to this specification.

DAVID ROBERTSON BRUCE.
